UNITED STATES PATENT OFFICE.

ALEXANDER HUSON, OF PERTH AMBOY, NEW JERSEY.

HEAD-PROTECTING ATTACHMENT FOR RAINCOATS.

Application filed February 24, 1922. Serial No. 538,905.

To all whom it may concern:

Be it known that I, ALEXANDER HUSON, a citizen of the United States, residing at Perth Amboy, in the county of Middlesex and State of New Jersey, have invented new and useful Improvements in Head-Protecting Attachments for Raincoats, of which the following is a specification.

One object of my present invention is the provision of a simple and efficient, detachably connected head protector for use on raincoats.

Another object is the provision in the raincoat of a pocket in which the head-protecting attachment can be carried when not in use.

To the attainment of the foregoing, the invention consists in the improvement as hereinafter described and definitely claimed.

20 In the accompanying drawings, forming part of this specification:—

Figure 1 is a front elevation showing my novel attachment in use on a raincoat.

25 Figure 2 is a view showing the attachment in vertical section.

Figures 3 and 4 are enlarged detail vertical sections showing portions of the attachment, hereinafter explicitly referred to.

20 Figure 5 is a detail broken elevation showing the pocket at the inner side of the back of the coat for carrying the head protecting attachment when the latter is not in use.

35 Similar numerals of reference designate corresponding parts in all of the views of the drawings.

The raincoat 1 is generally of the ordinary well-known construction, but in accordance with my invention it is provided about its neck portion 1^a with a circular series of spaced snap-fastener members 2, Figure 2, and is equipped at the inner side of its back 3 with a pocket 4, normally closed by a detachably fastened flap 5.

45 My novel head-protecting attachment 6 is preferably, though not necessarily, formed of the same material as the coat 1, and when not in use the said attachment is compactly folded and carried in the pocket 4. For the detachable connection of the attachment to the coat 1, the attachment is provided with snap fastener members 7 complementary to the fasteners 2. In the preferred embodiment illustrated, the fastener members 2 are of the male type, and the fastener members 7 are of the female type.

55 The attachment 6 is preferably shaped as

shown so as to entirely enclose the head and neck, and it is equipped with a mouth opening 8, see dotted lines in Figure 1, and full lines in Figure 4, framed transparent lenses 9, and a foraminous disk 10 of appropriate material, the said disk 10 being arranged between the opening 8 and the lenses 9 for the supply of air to the nostrils of the wearer. As shown in Figure 4 the disk 10 is framed as designated by 11, and its foraminations 12 are inclined as shown so as to lessen the liability of water entering the attachment. At its opposite sides the attachment 6 is provided with framed foraminous disks 13, one of which is shown in Figure 3. These disks 13 are designed to enable sounds to reach the ears of the wearer, and its foraminations 14 are inclined as shown to prevent water getting into the attachment.

In the present and preferred embodiment of the invention, a flap 15 is employed in conjunction with the mouth opening 8, the said flap being connected at 16 to the attachment 6, and being adapted to be secured in closed and open positions by snap fasteners 17 and 18, respectively.

It will be apparent from the foregoing that my novel attachment 6 is adapted to be quickly and easily placed over the head and connected to the coat 1, and when so placed and fastened the attachment is adapted to effectively protect the head and neck of the wearer. It will also be appreciated that the attachment is susceptible of being readily disconnected from the coat and as readily folded and placed in the pocket 4.

I have entered into a detailed description of the construction and relative arrangement 95 of the parts embraced in the present and preferred embodiment of my invention in order to impart a full, clear and exact understanding of the said embodiment. I do not desire, however, to be understood as confining myself to the said specific construction and relative arrangement of parts inasmuch as in the future practice of the invention various changes and modifications may be made such as fall within the scope of my 100 invention as defined in my appended claim.

Having described my invention, what I claim and desire to secure by Letters-Patent, is:—

110 A head protector adapted to be applied to a body garment comprising a globular portion of flexible material adapted to receive

the head of the wearer and a flaring neck portion adapted to receive the neck of the wearer, means for detachably connecting the neck portion with the body garment, the globular head portion being provided with openings adapted to register with the ears, eyes, nose and mouth of the wearer, relatively rigid frames applied to the head portion and surrounding the ear, eye and nose openings thereof, imperforate transparencies mounted in the frames which register with the eye openings, perforated disks mounted in the frames which register with the ear

and nose openings, the axes of the openings in the said disk being disposed at acute 15 angles to the frames of the disk, and a flap of flexible material secured to the head portion above the mouth opening, and means for releasably securing said flap in an open position with relation to the mouth opening, 20 and means for securing said flap in a closed position over the mouth opening.

In testimony whereof, I affix my signature.

ALEXANDER HUSON.
